UNITED STATES PATENT OFFICE.

WILLIAM J. HAMMER, OF BOSTON, MASSACHUSETTS.

SAFETY DEVICE FOR ELECTRIC CIRCUITS.

SPECIFICATION forming part of Letters Patent No. 400,669, dated April 2, 1889.

Application filed December 9, 1886. Serial No. 221,087. (No model.)

To all whom it may concern:

Be it known that I, WILLIAM J. HAMMER, of Boston, in the county of Suffolk and State of Massachusetts, have invented a certain 5 new and useful Improvement in Safety Devices for Electrical Circuits, of which the following is a specification.

In my application filed November 19, 1886, Serial No. 219,368, I have set forth an arrangement of safety-catches for electrical circuits wherein the safety-catches are so arranged that when one safety-catch is destroyed another of greater capacity may be switched into its place in the circuit.

15 My present invention relates to an improvement on this; and it consists, mainly, in providing means for automatically substituting one safety-catch for another. I prefer to perform this operation by mechanical means, 20 though it may be done wholly or in part electrically.

I have devised several different ways of carrying my invention into effect, which are illustrated in the accompanying drawings.

25 Figure 1 illustrates the mode of operation in which a weight is used. Fig. 2 shows the use of a spring. Fig. 3 illustrates the employment of a magnet, and Fig. 4 that of a solenoid, for the purpose of replacing the safety-catch.

Referring first to Fig. 1, 1 2 represent a portion of an electrical circuit, which normally includes a safety catch or strip of fusible metal, *a*. This safety-catch is secured to 35 metal plates *b b'*. From plate *b'* a conductor, *c*, extends to conductor 1, which is a part of the circuit. Passing through or connected with plate *b* is a metal arm or two arms, *d d'*. To *d* is connected circuit-conductor 1. At or 40 near the end of *d'* is a weight, *e*. Immediately below the plate *b* is a contact-plate, *f*, preferably a double plate, as shown, so that the plate *b* is adapted to enter between its parts. From plate *f* a safety-catch strip, *a'*, 45 extends to a plate, *f'*, from which a conductor, *g*, extends to conductor 2. When the safety-catch *a* is fused and destroyed by an excessive current on the line, the arm *d d'* is released and falls by gravity, assisted by the 50 weight *e*, so that plate *b* makes contact with *f* and closes circuit from 1 to 2 through safety-

catch *a'*, which is made of greater conducting capacity than *a*, so that it is able to convey the current. This difference of conductivity is illustrated in the drawings by making the 35 strip *a'* in each figure slightly wider than the strip *a*. It may, however, evidently be accomplished in other ways. In the form shown in Fig. 2 the automatic substitution of the safety-catch is accomplished by the action of a 60 spring, *h*, instead of by gravity. Such spring is attached to arm *i*, and when the normal safety-catch *a* breaks the spring draws the arm up and closes circuit through safety-catch *a'* instead. In both these forms it will 65 be seen that the substitute safety-catch is held mechanically out of circuit, and is placed therein by automatic mechanical means.

In Fig. 3 two double contact-plates, *k* and *k'*, are shown connected, respectively, through safety-catches *a* and *a'*, with conductor 1. A pivoted arm, *l*, included in the circuit, rests normally in contact with plate *k*, being held there by a magnet, *m*, whose coils are included in the circuit. When the circuit is broken 75 by the destruction of the safety-catch *a*, the magnet ceases to attract the arm, and the spring *n*, attached to said arm, at once draws it up against the contact *k'*, bringing safety-catch *a'* into the circuit. A substantially similar 80 construction is shown in Fig. 4. The circuit is thrown into a coil, *o*, and the arm *l* has a magnetic extension, *p*, which forms a movable core for said coil. The effect is the same as that of the magnet in Fig. 3. In these forms the substitute safety-catch is held out of circuit electrically and placed therein mechanically.

It will of course be understood that while the magnet or solenoid is of sufficient strength 90 to hold the armature or core down it is not strong enough to draw it down when it is removed by the spring outside of the immediate magnetic field.

What I claim is—

1. The combination, with an electrical conductor, of a safety-catch normally in the circuit thereof, a substitute safety-catch of greater conducting capacity, and means for automatically placing the latter in circuit 100 upon the breaking of the former, substantially as set forth.

2. The combination, with an electrical conductor, of a safety-catch normally in the circuit, a switching device suspended by said safety-catch, and a substitute safety-catch of greater conducting capacity provided with suitable terminals situated beneath said switching device, whereby upon the breaking of the normal safety-catch the substitute is

switched automatically into circuit, substantially as set forth.

This specification signed and witnessed this 6th day of December, 1886.

WM. J. HAMMER.
